US0D1071575S

(12) United States Design Patent (10) Patent No.: US D1,071,575 S
Chen (45) Date of Patent: * Apr. 22, 2025

(54) COSMETIC MIRROR

(71) Applicant: Shenzhen Chunwei Technology Co., Ltd., Guangdong (CN)

(72) Inventor: Yu Chen, Guangdong (CN)

() Term: 15 Years

(21) Appl. No.: 29/952,936

(22) Filed: Jul. 18, 2024

(51) LOC (15) Cl. 06-07

(52) U.S. Cl.

USPC D6/308; D6/309

(58) Field of Classification Search

USPC D6/300, 308-310, 312

CPC A45D 42/00; A45D 42/10; A45D 42/16

See application file for complete search history.

(57) CLAIM

The ornamental design for a cosmetic mirror, as shown and described.

DESCRIPTION

FIG. 1 is a perspective view of a cosmetic mirror design showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a front side perspective view thereof, shown in an extended configuration.

FIG. 9 is a rear side perspective view thereof, shown in an extended configuration; and,

FIG. 10 is a front view thereof, shown in an extended configuration.

The broken lines in the drawings depict portions of the cosmetic mirror that form no part of the claimed design.

1 Claim, 10 Drawing Sheets
